UNITED STATES PATENT OFFICE

90,429

DESIGN FOR A BENT WINDOW GLASS

Herman A. Tidemann, Toronto, Ontario, Canada

Application December 30, 1932. Serial No. 46,663

Term of patent 14 years

To whom it may concern:

Be it known that I, HERMAN A. TIDEMANN, a British subject, residing at the city of Toronto, in the county of York and Province of Ontario, Dominion of Canada, have invented a new, original, and ornamental Design for Bent Window Glass, of which the following is a specification, reference being had to the accompanying drawing, forming part thereof.

Figure 1 is a front view of a bent window glass showing my new design.

Figure 2 is a side view.

The lower portion of the bent window glass is elliptical in shape. The upper portion is scalloped on either side curving arcuately to the top where it is capped with the arc of a circle which is approximately one half of the width of the frame where the scallop begins.

I claim:

The ornamental design for a bent window glass substantially as shown and described.

HERMAN A. TIDEMANN.
